UNITED STATES PATENT OFFICE

OVERTON SACKSTEDER, JR., OF MUNCIE, INDIANA, ASSIGNOR TO ALADDIN MANUFACTURING COMPANY, OF MUNCIE, INDIANA, A CORPORATION OF INDIANA

PORTABLE LAMP

Application filed January 21, 1928. Serial No. 248,370.

This invention relates to portable lighting stands or fixtures in which the illuminating element is supported by a stand structure of suitable formation and height to constitute 5 a floor lamp. For the general lighting efficiency required of a lamp of this character, there is provided a shade of relatively large size.

To provide improvements in construction 10 whereby the amount of space occupied by a lamp of the kind described, is minimized, and by which the range of usefulness of the lamp is at the same time increased, are the general objects of my invention. The more specific 15 purposes of the invention and as the same relate to structural features and details, will become apparent as the specification of my invention proceeds.

My invention is shown in the present application 20 as embodied in a portable stand of the electric floor lamp type, the height of same being about five feet.

The objects of my invention are accomplished by the new construction, combination 25 and arrangement of parts described in the following specification, and illustrated in the accompanying drawings. The invention is defined in the appended claims.

The several parts of the invention as they 30 appear in the different views in the drawings, are identified by suitable characters of reference.

Figure 1 is a front view of my improved 35 electric portable lamp.

Figure 2 is a side view of Figure 1, as seen in the direction of arrow 2.

Figure 3 is a sectional top plan view taken 40 on the line 3-3 in Figure 1.

Figure 4 is a top plan view of Figure 2, 45 the covering of the shade having been removed.

Figure 5 is an enlarged vertical central 50 sectional view taken on the line 5-5 in Figure 4, and showing in detail the stay-arm connection at the upper portion of the support column.

Figure 6 is a top plan view of the stay-arm.

Figure 7 is a view showing a stay-arm of modified form.

55 Figure 8 is a top plan view of Figure 7.

The base A as shown in the present embodiment of my invention, is of ornamental leaf-shaped triangular formation about thirteen inches in length. It may be of any suitable material, cast metal being preferred, and it is of such formation in cross section that a suitable amount of weight is provided at the marginal portions and at the downwardly disposed tips A¹, A², and A³. The head portion A⁴ of this base, at location equidistant 60 from the said tips A¹, A² and A³, is of suitable thickness in cross section, and is provided with a bore through which the stem of the support member may be inserted and there secured. See Figure 2.

Formed integral with the said head portion A⁴, is a foot A⁵ which extends downwardly to the plane of the bottoms of the tips A¹, A², and A³, and outwardly to a location slightly beyond the plane of the edges of the tips A¹ and A³, as shown in the sectional view in Figure 2, and in the plan view Figure 3. By this peculiar construction of the base there is constituted a stable foundation for the retention of the upright support member.

The lighting-device support member consists of a finished metal column B which is provided at its top portion with a body cup C in which the taped connections of the electric wires which extend from the conductor cord 1 to terminal connections in the sockets 2 are retained. Projecting upwardly from said cup C is a threaded stud D, the function of which will be presently referred to.

Adapted to be sustained at proper position on said column, is a translucent shade E and which may be of semielliptical formation in plan, as shown in Figure 4. This shade may be made of parchment, or cloth or other suitable material, its edges being secured to the members E¹, E² and E³ of the wire frame provided therefor. The top members E⁴ of this shade frame are secured to a connector head E⁵. This connector head which may consist of a finished metal disk is provided 95 with a central bore which passes the threaded stud D when the shade is placed in position.

The essential feature of the said shade is, that the connector head E⁵ of the frame members E⁴, is located in a position a distance 100

from the plane of the rearward side of the shade, and which distance is substantially the equivalent of the distance between the column B and the vertical surface of the foot A⁵ of the base A. While the detail just described is considered preferable, it will be understood that other suitable forms of connecting details may be used.

It is obvious that a lamp stand of the construction just described, is capable of affording efficient lighting, and that it occupies less space, is more economical of construction, and requires the use of less material, than do lamps of this class as hitherto constructed.

In households and dwelling quarters generally, the economy of space is not only desirable, but is necessary; and moreover, there are certain locations with reference to doors or windows, or to articles of household furniture, which while unavailable for the use of a floor lamp or table lamp of standard type with its relatively large centrally supported shade, are available to be conveniently and practicably occupied by a lamp stand of the present invention. Further advantages of my invention are that when the lamp is disposed with its base immediately adjacent to or in close proximity with the wall, there is not only an artistic effect (the shape performing the function of a sconce or shield) but there is obtained a refraction of the light from the wall, thereby imparting to the room interior an intensified but diffused illumination. At the same time there is no impairment of the efficiency of the light as emanating from the frontal portion of the shade. Another advantage of my invention is that of the shade giving the appearance of being partially sunken in the wall, thereby contributing to the artistic treatment of the room in which it is used. My improved lamp while effective and useful in any location, is especially intended for the uses above indicated.

The surface alignment and contour of flooring, and the thickness of base-board finishings in household interiors being more or less varied, and which variations may require the lamp stand to occupy positions varied accordingly, I have provided a stay-arm whose purpose is to stay the lamp stand against tendency to lean from true vertical position. This said stay member also performs the function of a handle by which the lamp stand may be lifted or moved to desired position without the necessity of touching the shade or column. This stay arm G may be made of cast or sheet bar metal; is of curved formation, as shown in Figures 4 and 6, and is provided with spaced recesses G¹, as plainly shown in Figure 5. The bore of the shank of said stay arm is of diameter that the arm is retained in close fitting but movable engagement with the stud D. By means of the finished knob F the connector head may be

clamped and held in tightened engagement with the said stay-arm, and which said stay-arm, in turn is clamped and held securely in engagement with the top of the body cup C.

The normal or retracted position of the stay arm is indicated by the dotted lines in Figure 4, or it may normally occupy any other position in which it may be disposed within the area of the interior of the shade. To stay the lamp stand, the arm G is moved rotatively on the stud D, to such position that its end portion rests in contact with the wall, the position of the wall, for example, being that indicated by the dotted lines 4 in Figure 2. While this lamp stand is essentially a portable device and is intended to be used as such, it is understood that if for any reason it may be desired to fasten the lamp stand in its position adjacent to the wall, a nail or screw provided in the wall may be engaged by one of the recesses G¹. It is obvious that by reason of the curvature of the stay arm, the variations in distance between the wall surface and the column of the lamp are easily compensated by adjustment of the position of the stay-arm.

A stay arm of modified form, may be made of cast or pressed sheet metal in the fanciful form K as shown in Figure 7, the end portions K¹ of which extend a suitable distance from the center of the column, as shown in the plan view Figure 8. This arm is adapted to be disposed at any desired height on the column, and may be fastened at position by a set screw K².

Whereas in the present specification I have shown the general construction, forms, and details considered preferable for carrying my invention into effect, I desire it to be understood that modifications, alterations and changes may be made therein, within the scope of the invention as defined by the appended claims, without departing from the nature or spirit of my invention or sacrificing any of its advantages.

What I claim as my invention, and desire to secure by Letters Patent, is—

1. A lamp of the kind described comprising a base, a relatively long lighting-device column extended upwardly from one side of the base member, and which said column is provided with a fixture cup having the usual threaded stem, an arm of curved formation in plan and which extends at a right angle to and whose one end is journaled on said stem, a semi-circular shade one side of which is open, a connection adjacent to the open side of the shade to engage the said stem and arm, and a knob screwed on said stem to unite the shade and the arm with the said column, and to hold the shade and the arm in the positions to which they are adjusted.

2. A lamp stand of the kind described, comprising a base, a relatively long lighting device column extended upwardly from a side

portion of the said base and which has a threaded top stem, an arm which is pivotally retained on said stem, a semi-circular shade one side of which is open, a connection adjacent to the open side of the shade to engage the said stem and arm, and a knob screwed on said stem to unite the shade and arm with the column, and to hold the shade and the arm in the positions to which they are adjusted.
